Harry M. Brown.
ATTORNEY.

UNITED STATES PATENT OFFICE

FRANK O. WELLS, OF GREENFIELD, MASSACHUSETTS

DIE BLANKS AND METHOD OF MAKING DIES

Application filed March 3, 1927. Serial No. 172,320.

This invention relates to dies, die blanks and methods of making the same.

One object of the invention is to provide an improved process of making thread cutting dies which will facilitate the manufacture of such dies, reduce their cost of manufacture and produce a more uniform and durable product.

Another object is to provide an improved die blank which may be economically manufactured and which may be readily transformed by punching, threading and finishing operations into a finished thread cutting die.

Other objects will be in part obvious and in part pointed out hereinafter.

One illustrative die blank and one illustrative die which may be made therefrom are shown in the accompanying drawings, 20 in which:

Fig. 1 is a top plan view of a die blank embodying the invention.

Fig. 2 is a sectional view taken on the line 2—2 of Fig. 1.

Fig. 3 is a top plan view of the die blank after the web portion connecting the ends of the lands has been punched out and the ends of the lands have been reamed.

Fig. 4 is a vertical sectional view taken on the line 4—4 of Fig. 3 and illustrating the finished opening through the web.

Fig. 5 is a top plan view showing in dotted lines the threads which have been cut on the ends of the lands.

Fig. 6 is a vertical sectional view taken on the line 6—6 of Fig. 5 and showing the threads on the ends of the lands.

Fig. 7 is a top plan view illustrating how the lands are relieved.

Fig. 8 is a top plan view of a two part die made from the blank of Fig. 1.

The die blank selected for illustration and which is particularly well adapted for use in producing the two part die shown in Fig.

45 8, consists of two body portions 1 and 2, preferably of steel and connected by a thin web 3, preferably of the same material and located centrally of the blank. Body portion 1 is provided with lands 7 and 10, and body portion 2 is provided with lands 8 and

9. The lands of the respective body portions are oppositely disposed in spaced relationship and are preferably formed integrally with their respective body portions. Each body portion is preferably depressed between its lands on either side of the web 3 to provide chip receiving recesses 13.

The die blank just described is preferably produced from a steel bar or block by a drop-forging operation on a drop-forging machine; the forming dies of the drop-forging machine being so constructed and arranged as to form the two body portions of the blank with their respective lands and recesses connected by the thin web 3—the immediate result of the forging operation being substantially the completed blank shown in Fig. 1.

To produce a complete thread cutting die from the die blank of Fig. 1, the blank is subjected to a series of operations now to be described.

When the blank comes from the drop-forging machine, its outer surfaces are preferably ground or finished in the usual way. The center of the web 3 which lies between the ends of the lands 7, 8, 9 and 10, is then removed, preferably by a punching operation, to provide an opening 6 for reaming and threading the ends of the lands. A reamer is then inserted into the opening 6 and the ends of the lands are reamed out to provide the desired spaced relationship of the opposed ends. The ends of the lands are then provided with cutting threads 11, preferably by means of a die hob having threaded flutes, which will accurately center itself in the reamed opening and form threads of uniform depth on the ends of the lands 7, 8, 9 and 10.

Following the threading operation, the upper and lower edges of the lands are preferably relieved as at 12, to provide suitable clearance back of the cutting threads.

Suitable identifying and size numbers may be stamped on the respective body portions 1 and 2.

To provide a two piece die such as is shown in Fig. 8, the body portions 1 and 2, with their respective lands and recesses, are

separated by removing the remaining portions of the web 3, preferably by punching out such portions.

Either in the forging or finishing operation the side edges of the die may be angled as indicated at 5 in Fig. 2 to permit the die to be reversed in the collet.

The completed dies are usually hardened and tempered.

10 Among other advantages, the invention produces a better die at a considerable saving in the cost of manufacture. Heretofore thread cutting dies have been produced from a bar or block of steel by expensive 15 milling or drilling operations, or from a die blank of such character as to require subsequent expensive milling or drilling operations. Applicant's process, on the other hand, produces by an inexpensive drop-forging 20 operation, a die blank having lands formed thereon and connected by a thin web of metal, which web may be subsequently removed by an inexpensive punching operation, thus eliminating entirely the expensive 25 drilling operation of the prior art.

It is well known that in a cross-section of a bar of steel the center of the bar is of poorer quality and less durable than the outer portions of the bar. When the lands 30 of the die are formed by a drilling operation at the center of the bar, the poor quality of the material impairs the wearing qualities of the threads. Applicant's process of forging a die blank with formed lands compresses and hardens the material forming the lands, thus refining the material of the lands and rendering it more durable for subsequent thread cutting operations.

The formation of the lands and the chip- 40 receiving recesses in the forging operation results in a saving of material and labor.

The invention is particularly advantageous in the manufacture of the two piece die shown in Fig. 8. Heretofore the lands of a 45 two piece die have been produced by a drilling operation, with the result that there is a more or less lack of uniformity in the dimensions and spaced relationship of the lands. Forging the lands and maintaining 50 the two parts of the die in fixed relationship during the punching, reaming and threading operations results in an accuracy and uniformity in the lands which are difficult to attain by prior methods.

55 It will be understood that the invention is not to be limited to the particular embodiment thereof shown for purposes of illustration and that all of the features of the invention need not be used conjointly, as 60 the invention may be variously embodied and the inventive features thereof may be used in different combinations and sub-combinations, as defined in the sub-joined claims.

What I claim is:

65 1. The method of simultaneously form-

ing a two part die which consists in first forging a blank with an integral thin web which connects the two spaced die portions, with the lands of each die spaced and located opposite each other and having chip recesses back of the lands, next reducing the blank to the correct finished thickness, next forming an opening through the web and between the lands, next finishing the opposite edges of the lands to size, next forming threads on the lands and relieving the threads, next removing the thin web to separate the dies, then hardening and tempering.

2. Steps in the method of forming thread cutting dies which consist in first forging a blank to produce oppositely located recesses and lands which are connected together with a web, then removing the center part of the web, then simultaneously finishing all of the ends of the lands, then inserting a die hob in the opening formed by removing the center part and forming threads on the finished ends of the lands, then relieving the formed threads, then removing the remaining portions of the connecting web for separating the dies.

3. Steps in the method of forming two part dies which consist in first forging a blank to produce recesses and lands on its opposite sides, then forming an opening in that part of the web which is adjacent the lands, then inserting a die hob in the opening and forming threads on the lands, then separating the dies by removing the remaining web which connects the dies.

4. Steps in the method of forming two part dies which consist in first forging a blank to produce recesses and lands on its opposite sides, then forming an opening in that part of the web which is adjacent the lands, then inserting a die hob in the opening and forming threads on the lands, then separating the dies by removing the remaining web which connects the dies, then hardening and tempering, as described.

5. The method of making thread cutting dies which is characterized by forging a die blank having two body portions provided with lands and connected by a thin web, removing that portion of the web which lies between the ends of the lands, forming threads on the lands, and removing the remaining portions of the web to provide a two piece die.

6. The method of making thread cutting dies which is characterized by forging a die blank having two body portions provided with oppositely disposed recesses and lands and connected by a thin web, removing that portion of the web which lies between the ends of the lands, forming threads on the lands, and removing the remaining portion of the web to provide a two piece die.

7. The method of making thread cutting

- dies which is characterized by forging a die blank from a block of metal to produce as the immediate result of the forging operation a die blank having a plurality of lands connected at their ends by a thin web of metal, removing the web between the ends of the lands, and forming threads on the lands.
8. The method of making thread cutting dies which is characterized by forging a die blank from a block of metal to produce as the immediate result of the forging operation a die blank having a plurality of lands connected at their ends by a thin web of metal and oppositely disposed recesses connected by a thin web of metal, removing the web between the ends of the lands, forming threads on the lands, and removing the web between the recesses.
9. As an article of manufacture, a forged metal blank for use in making thread cutting dies, comprising a body portion, and a plurality of lands formed within the body portion and connected at their ends by a thin web of metal; whereby a punching operation will remove the web from between the ends of the lands and permit the finishing and threading of said ends.
10. As an article of manufacture, a forged metal blank for use in making thread cutting dies, comprising a two part body, each part being provided with formed lands and the two parts being connected by a thin web of metal; whereby punching, threading and finishing operations will complete the formation of a two piece die.
11. The method of making thread cutting dies which is characterized by forging a die blank having a plurality of body portions provided with lands and connected by a thin web, removing that portion of the web which lies between the ends of the lands, forming threads on the lands, and removing the remaining portion of the web to provide a multiple piece die.
12. The method of making thread cutting dies which is characterized by forging a die blank from a block of metal to produce as the immediate result of the forging operation a die blank having land forming material located centrally of the blank and a plurality of recesses oppositely disposed on either face of the blank and positioned adjacent and around the land forming material and separated by a thin web of metal, forming cutting threads in the land forming material, and removing the web which separates the recesses.
13. As an article of manufacture, a forged metal blank for use in making thread cutting dies comprising a body portion, land forming material located centrally therein, and a plurality of recesses oppositely disposed on either face of the blank and positioned adjacent to and around the land forming material and separated by a thin web of metal located substantially in the central horizontal plane of the blank.
